UNITED STATES PATENT OFFICE.

ERNEST PATEY, OF NORBURY, ENGLAND.

TABLE ADAPTED TO BE USED AS COOKERY CABINET.

Application filed February 13, 1922. Serial No. 526,348.

To all whom it may concern:

Be it known that I, ERNEST PATEY, a subject of the King of Great Britain, residing at Kempshott, London Road, Norbury, in the county of Surrey, in England, have invented a new and useful Improvement in Tables Adapted to be Used as Cookery Cabinets, of which the following is a specification.

10 This invention has for its object to provide a table which is adapted to be used as a cookery cabinet and to conveniently hold all the necessary materials and appliances used in cookery.

15 The table according to my invention comprises legs and framing of the usual kind, having a top made in two sections, one of which is movable and beneath which is arranged a hinged box or cabinet adapted to be lifted with the movable section of the table top.

In the accompanying drawings, Fig. 1, is a sectional elevation showing the invention closed for use as a table in full lines, and 25 open for use as a cookery cabinet in dotted lines; Fig. 2, is a plan with the table top removed and the cabinet in its closed position; Fig. 3, shows a suitable form of lock for securing the table top to the cabinet, 30 and Fig. 4, shows an arrangement for locking the cabinet and table top to the framing.

According to the invention I provide table legs *a* and framing *b* of the usual kind but having an underneath board *c* completely 35 closing in the framing *b*.

The table top is made in two portions *d* and *e*, the portion *d* being secured to the framing *b* in the usual manner. The portion *e* is hinged to the portion *d* by any 40 suitable hinges *f* that will present a flush surface when the portion *e* is in its closed position, and is preferably larger than the portion *d* so that when folded back it will give a large area upon which to work.

45 The underside of the portion *e* is covered with enamelled iron or any other suitable material *e'* to serve, when folded back, as a clean and hygienic surface for rolling pastry and the like.

50 Within the framing *b* and hingedly attached to a partition *b'* I provide a box *g* having shelves *h* adapted to hold receptacles *i* containing such materials as currants, sugar, rice and the like, and also having a 55 small cupboard *h'* provided with sliding doors to hold sundry packages.

The box *g* is provided with hinged arms *k* which slide upon runners *l* provided with recesses *m* to hold the box in its upright position when it has been raised. 60

A suitable catch *n* is provided to lock the box to the portion *e* of the table top so that when the latter is raised, it raises the box *g* with it. A convenient form of catch is 65 shown in Fig. 3.

A slotted plate *o* is let into the portion *e* and a rod *p* having two projections *p'* at one end and a handle *p''* at the other is connected to the box *g* in such a manner that when the parts *e* and *g* are placed together 70 the projections *p'* pass through the slot in the plate *o* and the handle is then turned so that the projections catch the sides of the plate as will be understood. The slot allows for the different movements of the parts *e* 75 and *g*.

In the space between the board *c* and box *g* I provide a board *q* which can be used for chopping suet and the like.

The drawer *r* is made the whole width 80 of the framing *b* and is provided with a handle *s* at both ends. It is divided through its centre by a partition *t* and one half is again divided by partitions *u* to provide spaces for knives, forks, and spoons, and also 85 for receptacles for tea, cocoa and the like. The other half of the drawer is adapted to be used as a flour bin and is provided with a cover *w* sliding in slots *x*. A pastry roller hangs on two fittings in the flour bin. A 90 ball or other suitable catch *y* is fitted at each end of the drawer to keep it in place when closed. It will be seen that a drawer so constructed can be drawn out much farther 95 than those at present provided, without fear of it coming out of its runners.

A spring catch *j* is provided to automatically lock the box *g* and table top *e* when closed so that the whole table may be lifted. 100 A convenient form of lock is shown in Fig.

4. A plate *z* is pivotally attached to the framing *m* one end being held away therefrom by a spring *z'*. A metal or other projection *z''* is provided on the box *g*, and when the latter is closed down, it passes the plate *z* and cannot return. A rod *z'''* passes through the framing *b* to release the plate *z* as will be readily understood. 105

I claim:

In a combined table and cookery cabinet, 110 the provision of a table frame having a top formed in two portions, one of which is fixed

to the table frame, the other being hinged thereto and movable, and a box or cabinet hinged to the table frame and adapted to be moved with the movable portion of the table 5 top, means for locking the box or cabinet to the movable portion of the table top to enable the two to be drawn up together until the cabinet is in a vertical position, said movable portion of the table top being then 10 capable of being unlocked from the said box or cabinet and folded back up on to the fixed portion of the table top to form a working

space, means for holding the box or receptacle in its vertical position when the table is open, and means for locking the movable 15 portion of the table top and with it the box or receptacle to the table frame when the same are closed, the whole being constructed and arranged so that the same amount of leg room is available beneath the 20 table frame as with ordinary tables at present in use.

ERNEST PATEY.
